UNITED STATES PATENT OFFICE

112,486

DESIGN FOR AN AUTOMOBILE RADIATOR ORNAMENT

David J. Nusz, Hickam Field, Honolulu, Territory of Hawaii

Application July 5, 1938, Serial No. 78,284

Term of patent 7 years

To all whom it may concern:

Be it known that I, David J. Nusz, a citizen of the United States, residing at Hickam Field, Honolulu, in the Territory of Hawaii, have invented a new, original, and ornamental Design for an Automobile Radiator Ornament, of which the following is a specification, reference being had to the accompanying drawing, forming part thereof.

I claim:

The ornamental design for an automobile radiator ornament, as shown.

DAVID J. NUSZ.
